(57) **CLAIM**

I claim the ornamental design for a manifold, as shown and described.

DESCRIPTION

FIG. 1 is a perspective view of a manifold, showing my design;

FIG. 2 is another perspective view of the manifold of FIG. 1;

FIG. 3 is a front elevation of the manifold of FIG. 1;

FIG. 4 is a rear elevation of the manifold of FIG. 1;

FIG. 5 is a top view of the manifold of FIG. 1;

FIG. 6 is a bottom view of the manifold of FIG. 1;

FIG. 7 is a left elevation of the manifold of FIG. 1; and,

FIG. 8 is a right elevation of the manifold of FIG. 1.

The broken lines shown in the drawings are for the purpose of illustrating portions of the article that form no part of the claimed design.
